UNITED STATES PATENT OFFICE.

CHESTER H. BEACH, OF RACINE, WISCONSIN. ASSIGNOR TO WISCONSIN ELECTRIC COMPANY, OF RACINE, WISCONSIN, A CORPORATION OF WISCONSIN.

SUPPORTING-CLAMP FOR SEWING-MACHINE MOTORS.

1,272,189.

Specification of Letters Patent.

Patented July 9, 1918.

Application filed June 21, 1915. Serial No. 35,350.

To all whom it may concern:

Be it known that I, CHESTER H. BEACH, citizen of the United States, residing at Racine, in the county of Racine and State of Wisconsin, have invented a certain new and useful Improvement in Supporting-Clamps for Sewing-Machine Motors, of which the following is a full, clear, concise, and exact description.

10 My invention relates to improvements in means for mounting sewing machine motors or other small motors.

The object of the invention is to provide a combined sewing machine motor and supporting bracket or clamp, which may be readily applied to and removed from the top of the usual sewing machine without necessitating any change in the latter or mutilating the wood of the table top.

20 In the accompanying drawings, I have illustrated two embodiments of my invention. The invention may be embodied in other forms, however.

Figure 1 is a side elevation of a motor 25 and its support, properly positioned with respect to the head of the sewing machine by means of projections which fit into the two belt holes, the usual sewing machine driving belt being dispensed with and a 30 short driving belt being used instead.

Fig. 2 is a top plan view of the support.

Fig. 3 is a side elevation of a modified form of motor and its support, the latter having one projection fitting into one of the 35 belt holes and another projection engaging the edge of the table top, the motor being adapted to drive the standard sewing machine belt.

Fig. 4 is a top plan view of the support, 40 the motor being shown in dotted outline.

In Figs. 1 and 2, the table or top of the machine is indicated by reference character 1 and is provided with the usual openings 2, 3 through which the driving belt passes 45 when the machine is operated by the foot treadle. These openings provide convenient points of attachment for the motor support or clamp, which, in the form illustrated, comprises two metal plates 4, 5 having sliding engagement with each other. Said members are provided with downward and inwardly bent extensions 6, 7 constituting jaws which project through the holes 2, 3 and grip the wood to secure the clamp in

plate. These jaws are preferably offset, 55 whereby the members 4, 5 do not cover the belt holes, but leave them substantially unobstructed. The member 5 is provided with additional extensions or ears 8 which are bent upwardly to provide supports for a 60 pin 9. A coiled spring 10 is secured at one end to said pin 9, and at the other end to a vertical post 11 carried by the member 4. The latter member slides between said pin and the member 5 and is confined therebetween and also between the vertical extensions or ears 8 whereby it is guided in its movement. The spring 10 constitutes the means for drawing the jaws 6, 7 together, and also maintains them in yielding engagement with the walls of the openings 2, 3. Suitable stops 12, 13 are provided on the member 4 to limit the sliding movement.

The outer or rear end of the metal plate 5 is bent to form a hook 14 which may be 75 conveniently grasped by the finger when it is desired to extend the spring 10 either in locating the clamp on the table or in removing it. Said member 5 is provided also with a lateral extension 15 consisting of the horizontal portion of a substantially U shaped plate, which is secured thereto. The member 5 and the lateral extension 15 constitute what may be termed an L-shaped supporting plate for the motor. The upright side 80 members 17, 18 of the plate 15 provide bearings for a rod or pin 19 about which the motor 20 is pivoted, said motor being provided with a pair of downwardly extending supports 21 having openings therein through 90 which said rod 19 passes. The motor, which may be of any suitable type, carries a pulley 22 in alinement with the pulley 23 on the sewing machine, a short belt 24 furnishing the driving connection in the present case, 95 although some other type of drive may be employed. In order to maintain the belt tension, a suitable spring 25 is coiled about the rod 19 and co-operates with the vertical support 21, tending to swing the motor in 100 the direction shown by the arrow in Fig. 1.

The shaft 19 has a disk 26 mounted thereon, the latter having a hub or extension 27 constituting a drum about which a cord 28 is wrapped to a greater or less extent, the 105 end of the cord being secured to said drum. The disk 26 has a resilient contact arm 29 carried thereby which arm is adapted to

travel over a series of stationary contacts 30 connected with the successive steps of a resistance, the latter being inclosed within the cylinder 31. The structure described 5 constitutes a combined speed controlling rheostat for varying the speed of the motor and a switch for starting and stopping it. The cord 28 passes over a pulley 32 mounted on the pin 9, said cord passing down- 10 wardly through the unobstructed opening 3 and being connected to the foot treadle of the machine (not shown) whereby the speed of the motor is varied by pressure of the operator's foot on said treadle. The pressure 15 of the foot is resisted by a second spring 33 coiled about the shaft 19 and tending to turn the rheostat in such direction as to stop the motor.

In order to prevent the clamp from injuring the woodwork, suitable rubber pads 34, 35 are provided on the undersides of the members 4, 15 respectively, whereby all the metal parts are raised above the surface of the wood and out of contact therewith.

25 It will be seen that the clamp permits the motor to be securely held in place on the machine in a convenient position toward the rear of the table whereby it is out of the way of the operator. It also insures proper 30 alignment of the driving wheel and the driven wheel. The motor is clamped in place without boring additional holes in the wood or otherwise injuring the table-top.

In the form of device shown in Figs. 3 and 35 4, the motor is so arranged as to drive the usual belt which connects the lower pulley with the upper pulley of the machine. It is supported preferably to the rear of the head of the sewing machine, as in the first form 40 of device illustrated, the elevation in Fig. 3 being the opposite side of the motor, as compared to Fig. 1. The motor 41, which may be of any suitable type, has secured upon the underside of its base one member 42 of a 45 clamp. The member 42 is L-shaped and the foot of the L is provided with a transverse slot 43 which receives a screw 44 by which said member 42 and a base-plate 45 are attached to the underside of the motor-frame. 50 Said member 42 extends rearwardly from the motor, and hence the slot 43 permits of the motor being adjusted to a slight extent either forwardly or rearwardly in order to locate the motor-shaft pulley 46 in proper 55 position with respect to the driving belt 47 of the sewing machine. The member 42, at its elbow, is provided with a downwardly extending portion 48, constituting one of the jaws of the clamp, said jaw, as shown most 60 clearly in Fig. 3, projecting through the opening 49 provided in the table-top 50 for the belt 47, without interfering with said belt. At its rear end the member 42 is provided with a headed stud 51 which passes 65 through a slot 52 in the other member 53

of the clamp, thereby holding the two members 52 and 53 together, with the member 53 slidably longitudinally of the member 52. At its rear end the member 53 is provided with a downwardly extending jaw 54 70 adapted to engage over the rear end of the table-top, and affording a convenient hook to be grasped by the hand when positioning the motor on the table, or when removing it. A coiled spring 55 serves to hold the jaws 75 48 and 53 in clamping relation with the table-top 50. It will be seen that by merely pulling the jaws 48 and 54 apart and inserting one of the jaws in the opening 49 and lowering the other over the rear edge 80 of the table-top and then releasing the jaws, the tension of the spring 55 will securely clamp the motor in position upon the machine.

The groove in the periphery of the motor-shaft pulley 46 is in position to receive the driving belt 47 of the machine, said driving belt normally extending into the groove but out of operative engagement with said pulley. That is to say, the periphery of the pulley 46 is in substantial alignment with the peripheries of the hand wheel pulley 56 and the belt-pulley (not shown) of the sewing machine. Pivoted upon the end of the motor-frame, near the base thereof, is a lever 57 which extends upwardly and is curved rearwardly over the motor-shaft. At its free end the lever 57 carries a pulley 58, adapted, when the lever 57 is operated, to engage the belt 47 and move the same into 100 operative relation with the pulley 46. The pulley 58 thus controls the operative engagement of the belt 47 with the pulley 46, whereby the driving of the belt 47 by the pulley 46 and the speed at which the sewing machine is driven are dependent upon the position of the pulley 58. When the pulley 58 is out of engagement with the belt 47, said belt is out of operative relation with the pulley 46. The lever 57 is normally held 105 by a spring 59 in the inoperative position shown in Fig. 3. A chain 60, secured at one end to the lever 57 and at its other end to the treadle (not shown) of the machine, permits of the lever 57 being operated through the medium of the treadle and being held at any position of its operation. The treadle may be, and preferably is, the usual foot treadle of the machine. The chain 60 extends over a guide-pulley 61 conveniently 110 mounted upon the member 53 of the clamp, and the portion of the chain 60 which runs over the pulley is preferably in the form of a coiled spring 62 which provides a more suitable running surface and at the same 115 time renders the chain 60 somewhat yielding. By suitably pulling upon the chain 60 the belt 47 may be more or less tightened with respect to the pulley 46, thereby controlling the speed at which the sewing machine is 120 125 130

driven. The method of control eliminates the necessity for a rheostat.

It will be understood that when the motor is utilized for operating the sewing machine in the manner just described, the usual connection between the drive-wheel of the sewing machine and the treadle will be made inoperative, such connection as is well known, consisting of a pitman extending from the treadle to the crank-shaft of the drive-wheel. If it be desired to operate the machine by foot-power in the usual manner, this may be done merely by restoring the operative connection between the treadle and the drive-wheel and disconnecting the lower end of the chain from the treadle. The position of the electric motor is such that it does not interfere with the driving of the machine by foot-power, though it may be readily removed from the table-top and with equal readiness be replaced when desired.

Although the two forms of motor-supporting bases disclosed are designed particularly for use in connection with sewing machine table-tops having belt holes already arranged therein, it is obvious that where a portable motor is to be mounted on some other form of support, the necessary hole or holes can be bored in the support. It is also apparent that various changes may be made in the constructions described without departing from the spirit of the invention.

The claims of the present application are directed more particularly to the combination of the motor and its supporting clamp. The structure shown in Figs. 3 and 4 is claimed more specifically in my co-pending application 155,593, filed March 17, 1917.

Some of the features illustrated herein are claimed in my Patent 1,252,317, issued January 1st, 1918, "Sewing machine motors".

Having thus described my invention, what I claim as new and desire to secure by Letters Patent of the United States is:

1. The combination with a sewing machine having a head, and a table provided with belt holes, of an electric motor adapted to drive said head, and a base on which said motor is mounted, said base having a projecting member which fits into one of said belt holes to aid in alining the motor with the head of the sewing machine.

2. The combination with a sewing machine having a head, and a table provided with openings therein, of an electric motor adapted to drive said head, and a base on which said motor is mounted, said base having relatively adjustable projecting hooking members which, in coöperation with one of said openings, serve to clamp said base and said motor to said table.

3. The combination with a sewing machine having a head and a table, of an electric motor adapted to drive said head, and

an L-shaped base, said motor being mounted on one arm of said base, the other arm of said base having projecting members which coöperate with said table to aline the motor with the head of the sewing machine.

4. The combination with a sewing machine having a head comprising a driven wheel and a supporting shaft therefor and a table provided with belt holes, of an electric motor having a base supported on the rear of said table, said motor being arranged with its armature shaft substantially parallel to said supporting shaft, and means associated with said base constituting a clamp arranged substantially in alinement with said belt holes, part of which clamp engages the rear belt hole to properly position said motor with respect to said driven wheel.

5. The combination with a sewing machine having a driven wheel, a shaft therefor, a supporting standard, and a table provided with belt holes, of an electric motor having a base resting on said table to the rear of said standard, said motor having an armature shaft substantially parallel to said first shaft and having a driving wheel thereon arranged substantially in the plane of said driven wheel and said base having means for engaging said rear belt hole to maintain said motor in proper position with respect to said driven wheel.

6. The combination with a sewing machine having a table with belt holes therein, a driven wheel, a shaft carrying the same and a supporting standard therefor, of a portable motor having a base with cushioning material on the bottom thereof to prevent marring of said table and to insure friction, said base resting on said table adjacent to one of said belt holes with the armature shaft of the motor substantially parallel to said first shaft, means on said armature shaft whereby said motor may drive said driven wheel, and means coöperating with said belt hole to maintain said motor in place.

7. The combination with a sewing machine having a head, and a table provided with belt holes, of a small portable electric motor having a base supported on said table between said head and the rear of said table, and equipped with rubber pads to prevent marring said table, said base being substantially parallel to said rear edge and having an extension arranged at right angles thereto, said extension having a spring coöperating with relatively movable projecting members, constituting a yielding clamp to hold said motor in place.

8. The combination with a sewing machine having a head and a table provided with an opening therein, of a small portable electric motor having a base supported on said table adjacent to said head, said base

- having rubber pads to prevent marring said table, being substantially parallel to the rear edge thereof, and having an extension arranged at right angles thereto, said extension having relatively movable projecting members constituting a clamp to hold said motor in place, one member engaging the wall of said opening, the other member engaging another substantially vertical wall of said table, and means for causing said members to grip said walls.
9. The combination with a sewing machine, of an electric motor, and means for supporting said motor in driving relation to the machine, said means being adapted to be clamped to the sewing machine table between a pair of vertical walls thereof.
10. The combination with a sewing machine having a head, and a table provided with belt holes, of an electric motor adapted to drive said head, and a base on which said motor is mounted, said base having projecting members fitting into said belt holes to align the motor with the head of the sewing machine.
11. The combination with a sewing machine having a head, and a table provided with belt holes, of an electrical motor adapted to drive said head, and a base on which said motor is mounted, said base having projecting, hook-shaped, members, fitting into said belt holes and being relatively adjustable to clamp said base and said motor to said table.
12. The combination with a sewing machine having a head, and a table provided with belt holes, of an electric motor adapted to drive said head, and an L-shaped base, said motor being mounted on one arm of said base, the other arm of said base having projecting members fitting into said belt holes to align the motor with the head of the sewing machine.
13. The combination with a sewing machine having a head, and a table provided with belt holes, of an electric motor adapted to drive said head, and an L-shaped base, said motor being mounted on one arm of said base, the other arm of said base having projecting, hook-shaped members fitting into said belt holes and being relatively adjustable to clamp said base and said motor to said table.
14. The combination with a sewing machine having a head, and a table provided with belt holes, of an electric motor adapted to drive said head, and an L-shaped base, said motor being mounted on one arm of said base, the other arm of said base having projecting, hook-shaped members fitting into said belt holes, one of said projecting members being stationary, and means for moving the other of said projecting members to clamp said base and said motor to said table.
15. The combination with a sewing machine having a head, and a table provided with belt holes, of an electric motor adapted to drive said head, and a base on which said motor is pivotally mounted, said base having relatively movable members constituting a clamp, one of which members cooperates with a belt hole to align the motor with the head of the sewing machine.
16. The combination with a sewing machine having a head, and a horizontal table provided with belt holes, of a base member supported on said table with rubber interposed between the two to prevent marring said table, a horizontally arranged pivotal member supported by said base, a motor above said pivotal member and mounted thereon whereby it may rock about said pivot to effect a driving connection with said head, and means on said base for positively engaging a substantially vertical wall of said table to prevent slipping of said motor on said table.
17. The combination with a sewing machine having a standard, a rotatable shaft supported thereby, a wheel to be driven mounted on said shaft, and a table provided with belt holes, of an electric motor having a driving wheel thereon arranged substantially in the plane of said driven wheel, a pivotal support for said motor, a base carrying said pivotal support, a spring biasing said motor to driving position, said base resting on said table between said standard and the rear edge of said table, and means on said base cooperating with one of said belt holes to positively position said motor.
18. A portable driving means for sewing machines comprising an electric motor, a base upon which said motor is mounted, said base having means thereon for clamping it to a sewing machine table between the wall of one of the belt holes therein and another wall thereof, said motor being pivotally mounted on said base.
19. A portable sewing machine motor comprising a base having rubber pads and having clamps thereon, one of which is arranged to fit within one of the belt holes, the other of which is arranged to engage another vertical wall of the sewing machine table, a horizontal rod supported above said base and a motor having a pair of downwardly projecting arms through which said rod passes, whereby said motor is pivotally supported above said base.
20. The combination with a sewing machine, of portable driving means therefor, comprising an electric motor having a downwardly projecting bracket, a horizontal supporting rod passing through the lower end of said bracket, means for supporting said rod above the table top and a clamp at right angles to said rod for holding the latter in proper driving position.

21. The combination with a sewing machine, of portable driving means therefor comprising an electric motor having a pair of downwardly extending arms thereon and having openings near the lower end thereof, a horizontal rod passing through said openings constituting a pivotal support for said motor, a pair of brackets supporting the opposite ends of said rod, and a base of which said brackets constitute a part, said base having means engaging one of the belt holes of the sewing machine table to position said motor.
22. The combination with a sewing machine having a head and a table provided with belt holes, of an electric motor adapted to drive said head, and a base for said motor, said base having a forward extension comprising relatively slidable members, each of which has an offset downwardly projecting jaw adapted to fit in one of the belt-holes, whereby said members do not overlie and obstruct said belt holes, and a spring for drawing said jaws toward each other to clamp the base to the table.
23. The combination with a sewing machine having belt holes in the table, of an electric motor, and means for supporting said motor in driving relation to the machine, said means comprising relatively movable members, downwardly extending projections on each of said members arranged in alinement with said belt holes, resilient means normally biasing said members toward each other, and an extension on one of said members arranged to be grasped by hand to separate said members against the action of said resilient means in installing or removing said motor.
24. The combination with a sewing machine comprising a table with belt holes, and a head including a wheel mounted about a horizontal axis, of a motor arranged with its armature shaft parallel to said horizontal axis and having a base resting on said table between the rear edge thereof and the rear belt hole, said motor being pivoted to said base about an axis also parallel to said first axis, a downwardly extending hook fixed to said base, and a slidible member having a second hook at its forward end and having means at the other end arranged to be grasped by hand to manipulate said hook.
25. The combination with a sewing machine, of an electric motor, and means for pivotally supporting said motor in driving position, said means comprising a pair of projecting hooks, and means projecting rearwardly from the forward hook, whereby the latter may be manipulated.
26. The combination with a sewing machine, of an electric motor, and means for pivotally supporting said motor in driving position, said means comprising a support with a pair of projecting members, and manually operative means for adjusting the relation of said members horizontally.
27. The combination with a sewing machine having a head, and a table provided with belt holes, of a base member having rubber feet supporting it on said table in elevated position, a motor pivoted to said base about a horizontal axis, a pair of hook-shaped members associated with said base, one of which is arranged to engage a belt hole, resilient means to move said hooks toward each other, and a handle projecting to the rear of the rearmost hook for the purpose of manipulating the forward hook.
28. The combination with a sewing machine having a head, and a table provided with belt holes, of a motor aligned with said head, a base supporting said motor, a forward extension on said base, downward projections on said extensions arranged to enter said belt holes, and flexible controlling means extending from said motor through one of said belt holes.
29. The combination with a sewing machine having a head including a hand wheel and a grooved pulley and a table with belt openings, of a sewing machine motor, a base therefor, a pivotal support for said motor arranged above said base, a grooved pulley on said motor, a driving belt connecting said grooved pulleys, an extension on said base arranged in alinement with said belt holes, offset hooks extending downwardly from said extension into said belt holes, a pulley on said extension arranged over the rear belt hole, and flexible controlling means extending from said horizontal pivot over said pulley and down through said belt hole.
30. The combination with a sewing machine having a head, and a table provided with belt holes, of an electrical motor adapted to drive said head, means for controlling said motor, a base on which said motor is supported, said base having a projection engaging one of said belt holes, a flexible member for said controlling means, and means for guiding said flexible member through a belt hole.
31. The combination with a sewing machine having a head, and a table provided with belt holes, of an electrical motor adapted to drive said head, means for controlling said motor, a flexible member for said means, and a base on which said motor is mounted, said base having projecting hook-shaped members fitting into said belt holes and being relatively adjustable to clamp said base and said motor to said table, and means for supporting said flexible member in vertical alinement with one of said belt holes, whereby said member may pass therethrough.
32. The combination with a sewing ma-

- chine having a head, of an electrical motor adapted to drive said head, a base on which said motor is mounted, said base having adjustable projecting members constituting a 5 clamp, means for controlling said motor, a flexible member for said means, and a pulley on said clamp arranged above one of said projecting members for guiding said flexible member.
- 10 33. The combination with a sewing machine having a head, and a table provided with belt holes, of an electric motor adapted to drive said head, and a base for said motor, said base comprising a pair of longitudinally slidable plates, one overlapping the other, means connecting said plates, clamping jaws extending downwardly from said plates, a coiled spring for sliding said jaws toward each other, and means for limiting said sliding movement.
34. The combination with a sewing machine having a head, and a table provided with belt holes, of an electric motor adapted to drive said head, and a base for said motor, said base having a forward extension comprising relatively slidable members, each having a downward hook adapted to enter one belt hole, and means for moving said hooks toward each other to clamp the table between said belt holes, whereby said motor and its base are supported on said table to the rear of said belt holes.
35. The combination with a sewing machine motor bracket and a table-top having openings therein, of means for pivotally mounting a motor on said bracket, yielding means tending to move said motor about said pivot in order to maintain the belt tension, jaws on said bracket arranged to enter
- said openings, and resilient means drawing 40 said jaws toward each other.
36. A motor support comprising an extension on the motor frame, a plate having supporting arms thereon, a rod passing through said extension and said arms, and 45 forming a pivotal support for the motor, said rod serving also as a switch actuating means, and jaws associated with said plate for securing said motor to a support.
37. A support for a motor comprising a 50 pair of parallel projections thereon, a base plate having a second pair of parallel projections arranged adjacent to said first pair, a freely rotatable rod passing through said projections and constituting a pivotal support 55 for the motor, said rod constituting also a rheostat controlling means, means on said base plate for gripping a support and pads for elevating said plate above said support.
38. A sewing machine motor support comprising parallel projections on the motor frame, a base plate having a pair of upright arms near one end thereof, a rod passing through said arms and said projections and 65 constituting a pivotal support for said motor, a motor rheostat mounted on said rod and controlled by the rotation thereof, a pair of coiled springs on said rod, one of which tends to rotate the rheostat arm, and 70 the other of which tends to swing the motor about its pivot, means on said plate for detachably securing the latter to a support and means for rotating said rod.
- In witness whereof, I hereunto subscribe 75 my name this 17th day of June, A. D. 1915.

CHESTER H. BEACH.
